UNITED STATES PATENT OFFICE.

HENRY O. SCHMIDT, OF NEW YORK, N. Y., ASSIGNOR TO SIMONS, BROTHERS & CO., OF PHILADELPHIA, PENNSYLVANIA.

DESIGN FOR A CANE OR UMBRELLA HANDLE.

SPECIFICATION forming part of Design No. 20,558, dated March 3, 1891.

Application filed February 6, 1891. Serial No. 380,517. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a new design for a cane or umbrella handle.

The shank part A extends upwardly, terminating on the one hand in a crook B and on the other hand in an upwardly and laterally extending knob C, which knob and shank are made smooth. The crook is ornamented by a series of longitudinal ribs uniting at the point, and said ribs are separated from the

body or shank portion A by roughened work E. The lower part of the shank or body A 20 is finished by a band D of highly-ornamented work.

The handle may be made of any suitable material.

Having now described my design, what I 25 claim as new, and desire to secure by Letters Patent, is—

The design for cane or umbrella handles, substantially as herein described and shown.

In testimony of which invention I have 30 hereunto set my hand.

HENRY O. SCHMIDT.
